UNITED STATES PATENT OFFICE.

GEORGE ARTHUR CHILDS, OF ARLINGTON, MASSACHUSETTS, ASSIGNOR TO DOMINIQUE A. HOMAN.

CONDUCTOR-WIRE TERMINAL.

Application filed June 10, 1924. Serial No. 719,162.

This invention relates to terminals for electric conductor wires.

The object of the invention is to provide a simple and efficient device of this character 5 equipped with means for quickly connecting it to a wire without the use of tools and by the use of which a strong, reliable connection is made and the frayed end of the insulating cover secured by the connector.

10 Another object is to provide a terminal of this character so constructed that one terminal may be used with many sizes of wire.

With the foregoing and other objects in 15 view which will appear as the description proceeds, the invention resides in the combination and arrangement of parts and in the details of construction hereinafter described and claimed, it being understood 20 that changes in the precise embodiment of the invention herein disclosed, may be made within the scope of what is claimed without departing from the spirit of the invention.

In the accompanying drawings:

25 Figure 1 represents a side elevation of a terminal constructed in accordance with this invention showing the first step of the application of the wire thereto.

Fig. 2 is a similar view showing the second step.

Fig. 3 shows the third step.

Fig. 4 shows a side elevation with the terminal in operative position on a wire; and

Fig. 5 is a transverse section taken on the 35 line 5—5 of Fig. 4.

The gist of the invention resides in providing a wire terminal having a head for connection with a binding post and equipped with a pliable tail adapted to be wound 40 around the wire to secure it to the terminal.

In the embodiment illustrated the terminal comprises a head 1 and tail 5 constructed of a sheet of soft copper struck out in the form shown in the drawings the head being 45 preferably bifurcated and the furcations 2 and 3 thereof arranged parallel and in the same plane for connection with a binding post. This head 1 has a wire receiving aperture 4 in the body portion thereof preferably in a plane intermediate between that of the furcations and is equipped with a longitudinal rearwardly extending flat tail 5 here shown extending edgewise at an oblique angle from one edge of head 1 and 55 which is equipped at its junction with said

head on its inner edge with a notch 6 for a purpose presently to be described. This tail 5 is designed to be twisted around the stripped end of the wire 10, said end being threaded through the opening 4 in the head 60 and then folded back flat against the body portion of the wire before the tail of the terminal is wrapped therearound thus binding all possible fray of the cover of the wire into the coil effecting a reinforcement 65 of the wire as well as a strong connection of the terminal thereto.

In the use of this terminal the wire 10 has the insulating cover 12 stripped from the end thereof for about two inches, more or less. This stripped end 11 is then threaded through the opening 4 from the front to the back of the terminal, as shown in Fig. 1. The end of the insulating cover 12 is then drawn up into the notch 6 of the terminal and the stripped end folded back 70 parallel with and in contact with the covered portion of the wire as shown in Fig. 2. These parts are then held together and the tail 5 is wound around them in the direction of the arrow a as shown in Fig. 3. After winding the tail tightly around the parallel stripped and covered portions of the wire as shown in Fig. 4 the terminal 75 will be securely connected with the wire and a reinforce formed at its connection with the wire.

From the above it will be obvious that one size of terminal may be used upon many sizes of wire, the copper from which the 80 terminal has been constructed being quite soft and pliable the tail 5 may be twisted into place very easily with the fingers without requiring any tools.

By twisting or winding the tail 5 around 85 the stripped end of the wire binding of all possible fray of the wire cover into the coil is effected and at the same time two or more absolute contacts with the stripped portion of wire at every turn of the coil 90 are obtained.

The terminal as shown is made substantially Y-shaped in form struck out of a sheet of soft copper so that the shank or tail 5 may be wrapped around the wire in 105 the manner above set forth.

I claim:

1. A wire terminal of the class described comprising a head formed at one end to engage a binding post, and a pliable exten- 110

sion of less width than the head extending from the other end thereof, the head being formed with an aperture to receive a wire about which the extension is adapted to be wound helically.

2. A wire terminal struck from a sheet of pliable metal comprising a head, a pair of parallel arms extending forwardly from the head, and a strip extending rearwardly

from one side of the rear end of the head ¹⁰ and forming an oblique angle with respect to the arms, the head being formed with an aperture to receive a wire about which the strip is adapted to be wound.

In testimony that I claim the foregoing ¹⁵ as my own, I have hereto affixed my signature.

GEORGE ARTHUR CHILDS.
